(No Model.)

W. D. CARTER.

PAINT CAN PRESS.

No. 366,619.

Patented July 12, 1887.

UNITED STATES PATENT OFFICE.

WILLIAM D. CARTER, OF BROOKLYN, ASSIGNOR TO VALENTINE & COMPANY,
OF NEW YORK, N. Y.

PAINT-CAN PRESS.

SPECIFICATION forming part of Letters Patent No. 366,619, dated July 12, 1887.

Application filed June 4, 1887. Serial No. 240,312. (No model.)

To all whom it may concern:

Be it known that I, WILLIAM D. CARTER, of Brooklyn, in the county of Kings and State of New York, have invented a certain new and useful Improvement in Paint-Can Presses, of which I declare the following to be a full, clear, and exact description, reference being had to the accompanying drawings, forming a part of this specification.

10 This invention relates to an improvement in paint-can presses; and the invention consists in a paint-can press constructed, combined, and arranged in the manner hereinafter shown, described, and claimed.

15 In the accompanying sheet of drawings, Figure 1 is a front elevation of the press in position for use. Fig. 2 is a vertical section in the plane indicated by the line $x\ x$, Fig. 1. Fig. 3 is a cross-section in the plane $y\ y$, Fig. 2. Figs. 20 4 and 5 are detail views of certain parts.

Similar letters of reference indicate like parts in the several views.

The particular class of presses to which this invention relates is such as are employed to force paint from a can through the spigot or gate thereof. Generally speaking, presses for this purpose are old and well known; but it is believed that my press possesses novel and valuable features, as will be seen from the accompanying drawings.

25 A represents the back or foundation plate of my press. At or near one end of this plate is fixed, in any desired manner, a bracket, B. This bracket is cast with a hollow interior head, a , open at each end, as at b , and with slots c in the sides thereof. The bracket has also fixed to it a projecting fulcrum, d . Within the hollow head a , and fitted to snugly slide therein, is a block, C. This block is slotted as 30 at e . Pivoted to this block at one end is a pawl, f , which is provided with a thumb-lever, g , and with a projection, h ; also in the block C is inserted a spiral spring, k , which projects somewhat and bears against the projection h 35 of the pawl f . Passing through the head of the bracket, B, and sliding through the same, is a ratchet-bar, D. This bar terminates at one end in a grooved collar, E, having two studs, l and m , and a groove, n , formed thereon and 40 45 50 therein.

In the base-plate A are formed slots F, and removably fitted in either of said slots, as may

be desired, is a shelf, G. This shelf is of such size and proportions as will enable it to support a paint-can when placed thereon, and it is 55 provided at one side with a bracket-catch, p , made of the form shown in the drawings, so that the shelf can be fixed into one of the slots F and readily removed therefrom, as may be desired. On the ratchet-bar D is placed a disk, 60 H, centrally perforated to receive the upper part of the collar E, but not to permit the lower flange, r , of the collar to pass through said perforation. Notches s and s' are made in the sides of the perforation, of such size as will 65 permit the studs l and m to pass through the same.

Passing through the slots c in the sides of the hollow head a is a lever, K. This lever also passes through the slot e in the block C, and 70 one end of the lever is pivoted to the fulcrum d .

Now, when my press is constructed substantially as described, it is operated in this manner: By means of screws passing through the base-plate A, or otherwise, it is fixed vertically to the wall or elsewhere. The shelf G is fixed in either one of the slots F of the base-plate A, the can of paint is placed on the shelf, and the disk H on the ratchet-bar D allowed to descend on the surface of the paint or on a diaphragm placed in the can. The gate or spigot near the bottom of the can is then opened and the lever K moved alternately up and down, and by that operation the pawl f engages in the teeth s of the ratchet-bar D, and so forces the 85 bar and its disk H downward, producing thereby sufficient pressure on the paint in the can to cause it to pass out of the spigot or gate. To remove the disk H from the paint or can, slight pressure on the thumb-lever g causes 90 the pawl f to disengage from the teeth s in the bar D, so that that bar may freely be moved up, passing through the hollow head a for that purpose. When pressure is removed from the thumb-lever g , then the spiral spring k exerts 95 its force to again push the pawl f into engagement with the teeth s of the bar D. The purpose of the collar E and its studs l and m and groove n is this: Paint-cans are sometimes provided with a diaphragm fitted within the cans and sold with them. These diaphragms have sockets in them, and it is to fit these sockets I provide the collar E on the bar D; and as well to adapt the press to cans which 100

have not such diaphragms, I employ the disk H, which is fixed to the collar E by means of the studs l and m and groove n, or which may be removed from the bar when not needed.

5 The purpose of making more than one slot F is, as is obvious, in order that the shelf G may be moved to meet the requirements of cans of different heights or lengths.

Having now described my invention, what I claim as new, and desire to secure by Letters Patent, is—

A paint-can press having the following elements, in combination: a base-plate, A, provided with slots F and a fulcrum, d, a bracket, 15 B, having a hollow head provided with open

ends b and slots c, a sliding block, C, fitted in the hollow head a, a lever, K, passing through said block and pivoted to the fulcrum d, a pawl, f, pivoted to the block C and provided with a thumb-lever, g, projection h, and spiral spring k, a ratchet-bar, D, a grooved and studed collar, E, fixed to said ratchet-bar, a shelf, G, with catch p, and a disk, H, perforated to fit said collar E of the bar D, all constructed and combined as and for the purpose described. 20 25

WM. D. CARTER.

In presence of—

A. S. HOMER, Jr.,
B. L. CHANDLER.
